SULPHONIC ACID AND CARBOXYLIC ACID DERIVATIVES OF 1,1'-DIARYL-3,3'-ARYLENE-5,5'-BIS-PYRAZOLONES

Herbert Kracker and Richard Schmid, Frankfurt-on-the-Main, Germany, assignors to General Aniline Works, Inc., New York, N. Y., a corporation of Delaware

No Drawing. Application March 9, 1934, Serial No. 714,888. In Germany March 11, 1933

4 Claims. (Cl. 260—45)

The present invention relates to sulphonic acid and carboxylic acid derivatives of 1,1'-diaryl-3,3'-arylene-5,5'-bis-pyrazolones.

We have found that sulphonic acid and carboxylic acid derivatives of 1,1'-diaryl-3,3'-arylene-5,5'-bis-pyrazolones of the formula:

wherein R stands for an aryl radical and R' for an arylene radical and wherein at least one of the radicals R and R' contains at least one substituent of the group consisting of sulphonic acid and carboxylic acid groups, which, hitherto, have not been described in literature, are obtainable by condensing in an aqueous medium arylene-bis-acetic esters of the formula:

20 with aromatic hydrazines of the formula:

30 wherein R and R' have the above indicated meaning and R'' stands for an alkyl radical to form the bis-hydrazone and then closing the bis-pyrazolone ring, likewise in water, the corresponding alcohol being split off. The formation of the bis-hydrazone and especially the ring-closure to the bis-pyrazolone occur without difficulty and with 35 very good yields.

35 As is known from the literature, pyrazolones without sulphonic and carboxylic acid groups are easily obtainable by causing molecular proportions of an arylhydrazine to react upon acyl acetic esters. The reaction velocity in these cases is so high that it is not possible to eliminate the hydrazone formed as intermediate product; there is directly formed the respective pyrazolone (cf. H. Wieland, "Die Hydrazine" (1913), page 126).

40 If acyl acetic esters are caused to react with sulphonated or carboxylated arylhydrazines the reaction velocity is much less. Thus it is possible, for instance, according to "Berichte der deutschen chemischen Gesellschaft", vol. 25, (1892), page 50

1948, to condense para-phenylhydrazine-sulphonic acid with acetoacetic ester only with an excess of the ester and even in this case only at temperatures of 150° C.—160° C. The yield is extremely low, as the author himself states. Experiments have shown that, when working in a solution of acetic acid of 50% strength, the yield is better but attains even then only 50% of the theoretical. Furthermore, according to the statements in *Chemisches Zentralblatt*, 1911, I, page 83, it is not at all possible to condense free phenylhydrazine-para-sulphonic acid with furoyl acetic ester and the formation of the corresponding pyrazolone from the sodium salt of phenylhydrazine-para-sulphonic acid and the same ester takes place only at a temperature of 170° C. and with lowest yield. It, therefore, was to be expected that the formation of pyrazolones from arylhydrazine-sulphonic acids would be prevented by stearic or like hindrance, especially also in view of the observations which Rowe (cf. *Chemisches Zentralblatt*, 1921, III, page 331) made during his experiments to use arylhydrazine-ortho-sulphonic acids for condensing reactions.

20 In view of the fact that the last named reactions occur much more slowly it is possible to eliminate the hydrazone from acyl acetic esters and sulphonated or carboxylated arylhydrazines, as will be seen from the examples of the present invention of the formation of bis-hydrazone from arylene-bis-acetic esters and arylhydrazines containing sulphonic- or carboxylic-acid groups. Only by further treatment of these hydrazone, for instance, with alkalies at higher temperatures, the corresponding pyrazolones are formed.

25 A characteristic feature of the present process lies in the fact that the new bis-pyrazolone derivatives are easily formed in an aqueous medium wherein the arylene-bis-acetic esters are insoluble which fact could not be expected in view of the statements in "Berichte der deutschen chemischen Gesellschaft" vol. 25, page 1948, and "Chemisches Zentralblatt" 1911, I, page 83. It had rather to be supposed that the reaction of sulphonated or carboxylated arylhydrazines with arylene-bis-acetic esters in an aqueous medium would not take place at all or only with bad yields, since according to Berend and Herms in "Journal für praktische Chemie" (2)74, page 125 et seq. the condensation of the water-insol-

uble terephthaloyl-bis-acetic ester with phenyl-hydrazine to the corresponding 1,1'-diphenyl-3,3'-(para-phenylene) 5,5'-bis-pyrazolone occurs only by heating the components in glacial acetic acid. Moreover, the use of an aqueous medium has the advantage over the reaction of acyl acetic esters containing heavy acyl radicals with hydrazine derivatives containing sulphonic or carboxylic acid groups, known according to literature, 10 that the desired pyrazolone derivatives are obtained with very good yields.

The formation of the bis-hydrazone occurs with especial advantage in acid solution, the ring-closure to the bis-pyrazolone is advantageously conducted in a neutral or alkaline medium. The condensation to the bis-hydrazone and the subsequent ring-closure are preferably effected in the same aqueous medium, without elimination of the bis-hydrazone.

20 The pyrazolones thus obtainable are valuable intermediate products for the manufacture of dyestuffs.

The following examples serve to illustrate the invention, but they are not intended to limit it thereto:

(1) 388 grams of 4'-hydroxy-3'-carboxy-4-sulpho-1,1'-diphenyl-sulphone-2-hydrazine are suspended in 2500 cc. of water of 60° C. to 65° C. and the whole is rendered weakly acid to Congo paper by means of sodium carbonate solution. Thereupon, 155 grams of terephthaloyl-bis-acetic ethylester are quickly added and the whole is stirred for about a quarter of an hour at 60° C. to 65° C. The reaction hereby becomes strongly acid to Congo paper. In the course of half an hour a solution of 80 grams of anhydrous sodium carbonate in water is slowly run in until the acid reaction to Congo has just disappeared. Now the reaction is still very acid to litmus paper; the whole is entirely dissolved to a brown-yellow solution. After stirring for 2 hours at 65° C. to 70° C., free hydrazine can no longer be detected by means of Fehling's solution, that is to say, the formation of the bis-hydrazone is finished. 50 50 grams of prepared chalk are then added and the mass is heated to from 83° C. to 85° C. to effect the ring-closure. The temperature is maintained for 2 to 3 hours, the whole is filtered by suction, while hot, and the hot solution is run into a mixture of 500 cc. of hydrochloric acid (specific gravity 1.163) and 300 grams of sodium chloride. The bis-pyrazolone formed of the formula

55 precipitates with a grey color and forms, after filtering with suction, washing and drying, a grey powder.

60 The yield of precipitated pyrazolone amounts to about 90% of the theoretical.

65 By using in the above example instead of terephthaloyl-bis-acetic ethyl-ester 143 grams of terephthaloyl-bis-acetic methyl-ester, the same 70 pyrazolone is obtained.

In a similar manner there are obtained from: terephthaloyl-bis-acetic ester and o-sulphophenylhydrazine 75 1,1'-di-(2'-sulphophenyl)-3,3'-(para-phenylene)-5,5'-bis-pyrazolone (yellow powder);

m-sulphophenylhydrazine
1,1'-di-(3''-sulphophenyl)-3,3'-(para-phenylene)-5,5'-bis-pyrazolone (grey-yellow powder);
p-sulphophenylhydrazine
1,1'-di-(4''-sulphophenyl)-3,3'-(para-phenylene)-5,5'-bis-pyrazolone (yellow powder);
o-carboxyphenylhydrazine
1,1'-di-(2''-carboxyphenyl)-3,3'-(para-phenylene)-5,5'-bis-pyrazolone (yellow powder);
2-chloro-4-sulphophenylhydrazine
1,1'-di-(2''-chloro-4''-sulphophenyl)-3,3'-(para-phenylene)-5,5'-bis-pyrazolone (yellowish-grey powder);
2-chloro-5-sulphophenylhydrazine
1,1'-di-(2''-chloro-5''-sulphophenyl)-3,3'-(para-phenylene)-5,5'-bis-pyrazolone (yellowish-brown powder);
1-sulpho-2-naphthylhydrazine
1,1'-di-(2''-naphthyl-1''-sulpho)-3,3'-(para-phenylene)-5,5'-bis-pyrazolone (reddish-brown powder);
3-carboxy-2-hydroxy-5-sulphophenylhydrazine
1,1'-di-(3''-carboxy-2''-hydroxy-5''-sulphophenyl)-3,3'-(para-phenylene)-5,5'-bis-pyrazolone (reddish-brown powder);
4'-sulpho-4-diphenylhydrazine
1,1'-di-(4''-diphenyl-4'''-sulpho)-3,3'-(para-phenylene)-5,5'-bis-pyrazolone (brownish powder).
Instead of the terephthaloyl-bis-acetic ester there may also be used its substitution products. There may be obtained, for instance, from chloroterephthaloyl-bis-acetic ester and m-sulphophenylhydrazine
1,1'-di-(3''-sulphophenyl)-3,3'-(chloro-p-phenylene)-5,5'-bis-pyrazolone (yellow powder);
2-chloro-4-sulphophenylhydrazine
1,1'-di-(2''-chloro-4''-sulphophenyl)-3,3'-(chloro-p-phenylene)-5,5'-bis-pyrazolone (yellow powder).
From nitroterephthaloyl-bis-acetic ester and p-carboxyphenylhydrazine
1,1'-di-(4''-carboxyphenyl)-3,3'-(nitro-p-phenylene)-5,5'-bis-pyrazolone (yellow powder);
1-sulpho-2-naphthylhydrazine
1,1'-di-(2''-naphthyl-1''-sulpho)-3,3'-(nitro-p-phenylene)-5,5'-bis-pyrazolone (reddish-yellow powder).
The yields of precipitated pyrazolone amount to about 90%.

(2) 188 grams of para-sulphophenylhydrazine are suspended in 1500 cc. of water of 55° C.-60° C.

55 and rendered feebly acid to Congo paper by means of sodium carbonate solution. 160 grams of isophthaloyl-bis-acetic ester are quickly added, whereupon the mass is stirred for half an hour. The reaction becomes again very acid to Congo paper. In the course of half an hour a solution of 50 grams of anhydrous sodium carbonate in water is then run in, whereby the whole is entirely dissolved. The solution still shows a strongly acid reaction to litmus paper. After stirring for 2 hours at 55° C.-60° C. the formation of hydrazone is finished and free hydrazine is no longer detectable. Thereupon, an aqueous solution of 50 grams of anhydrous sodium carbonate is added, 75

the whole is stirred for half an hour at 65° C.-70° C. and heated to 85° C.-87° C. This temperature is maintained for half an hour, the whole is filtered and worked up as described in Example 1. The 1,1-di-(4"-sulphophenyl)-3,3'-(m-phenylene)-5,5'-bis-pyrazolone of the following formula:

is obtained in the form of a brownish-yellow crystalline powder with a yield of about 85% of the theoretical.

In a similar manner there are obtained from:

Isophthaloyl-bis-acetic ester and para-carboxy-phenylhydrazine

1,1'-di-(4"-carboxy-phenyl)-3,3'-(m-phenylene)-5,5'-bis-pyrazolone (yellowish powder);

Isophthaloyl-bis-acetic ester and 2-methyl-4-sulphophenylhydrazine

1,1'-di-(2"-methyl-4"-sulpho-phenyl)-3,3'-(m-phenylene)-5,5'-bis-pyrazolone (brownish powder);

Naphthoylene-1,4-bis-acetic ester and 1-sulpho-2-naphthylhydrazine

1,1'-di-(2"-naphthyl-1"-sulpho)-3,3'-(1",4"-naphthylene)-5,5'-bis-pyrazolone (brown-yellow powder);

Naphthoylene-1,5-bis-acetic ester and 3-carboxy-2-hydroxy-5-sulpho-phenylhydrazine

1,1'-di-(3"-carboxy-2"-hydroxy-5"-sulphophenyl)-3,3'-(1",5"-naphthylene)-5,5'-bis-pyrazolone (brown-yellow powder);

Diphenyloyl-4,4'-bis-acetic ester and 2-chloro-4-sulphophenylhydrazine

1,1'-di-(2"-chloro-4"-sulphophenyl)-3,3'-(4",4"-diphenylene)-5,5'-bis-pyrazolone (yellow powder);

(3) 233 grams of 4-nitro-2-sulphonphenylhydrazine are suspended in 3000 cc. of water of

55° C.-60° C. and rendered feebly acid to Congo paper by means of sodium carbonate solution, 160 grams of terephthaloyl-bis-acetic ethyl-ester are quickly added and the mass is then stirred for half an hour. The reaction becomes again

very acid to Congo paper. In the course of half an hour a solution of 60 grams of anhydrous sodium carbonate in water is run in, until the reaction is no longer acid to Congo paper; the reaction is still very acid to litmus paper, the bis-hydrazone formed has precipitated with a pure yellow color. The whole is stirred for 2

hours at 60° C.-65° C. and again 50 grams of anhydrous sodium carbonate dissolved in water are added, whereby the reaction becomes distinctly

alkaline to brilliant yellow and dissolution begins. The whole is stirred for a further 1-2 hours at 60° C.-65° C. and 168 cc. of caustic soda solution (specific gravity 1.383) are added, whereby a clear solution is obtained. The temperature is raised to 65° C.-70° C., but not higher, since otherwise decomposition accompanied by frothing takes place. The whole is stirred for a quarter of an hour at the said temperature, cooled to 50° C., filtered and the filtrate is run into 600

cc. of hydrochloric acid (specific gravity 1.163)

and 600 grams of sodium chloride. Thereby, 1,1'-di-(4"-nitro-2"-sulphophenyl)-3,3'-(para-phenylene)-5,5'-bis-pyrazolone of the following formula:

precipitates with a brown-yellow color.

The yield of pyrazolone amounts to about 80% of the theoretical.

In a similar manner there are obtained from Terephthaloyl-bis-acetic ester and 2,5-di-sulphophenylhydrazine

1,1'-di-(2",5"-disulphophenyl)-3,3'-(p-phenylene)-5,5'-bis-pyrazolone (yellow powder);

Isophthaloyl-bis-acetic ester and 2-nitro-4-sulphophenylhydrazine

1,1'-di-(2"-nitro-4"-sulphophenyl)-3,3'-(m-phenylene)-5,5'-bis-pyrazolone (brown powder);

Chloroterephthaloyl-bis-acetic ester and 2-methyl-4,5-disulphophenylhydrazine

1,1'-di-(2"-methyl-4",5"-disulphophenyl)-3,3'-(chloro-p-phenylene)-5,5'-bis-pyrazolone (yellow powder);

Nitrotetraphthaloyl-bis-acetic ester and 4-nitro-2-sulphophenylhydrazine

1,1'-di-(4"-nitro-2"-sulphophenyl)-3,3'-(nitro-p-phenylene)-5,5'-bis-pyrazolone (brown-yellow powder);

Naphthoylene-1,5-bis-acetic ester and 2-nitro-4-sulphophenylhydrazine

1,1'-di-(2"-nitro-4"-sulphophenyl)-3,3'-(1",5"-naphthylene)-5,5'-bis-pyrazolone (brown powder);

Diphenyloyl-4,4'-bis-acetic ester and 2,5-di-sulphophenylhydrazine

1,1'-di-(2",5"-di-sulphophenyl)-3,3'-(4",4"-diphenylene)-5,5'-bis-pyrazolone (yellow powder).

In these cases too the yields are very good.

We claim:

1. The compounds of the following general formula:

wherein R and R' stand for radicals of the benzene, naphthalene or diphenyl series and wherein the radical R contains at least one substituent of the group consisting of sulphonic acid and carboxylic acid groups, representing well crystallized bodies, easily soluble in aqueous alkalies, capable of combining with diazo compounds.

2. The compound of the following formula:

5

10

15

25

30

35

40

45

50

60

70

75

representing a yellow crystallized body, easily soluble in aqueous alkalies, capable of combining with diazo compounds.

3. The compound of the following formula:

5

representing a brown-yellow crystallized body, easily soluble in aqueous alkalies, capable of combining with diazo compounds.

4. The compound of the following formula:

5

10

15

representing a reddish-brown crystallized body, easily soluble in aqueous alkalies, capable of combining with diazo compounds.
